UNITED STATES PATENT OFFICE.

ERNEST CANTELO WHITE, OF NEW YORK, N. Y., ASSIGNOR OF ONE-HALF TO R. FENTON FISHER, OF PHILADELPHIA, PENNSYLVANIA.

ELECTRIC LIGHTING FIXTURE.

Application filed October 7, 1926. Serial No. 139,991.

My invention relates to the construction of all types of electric lighting fixtures which include or support a lamp socket and a lamp shade.

5 One of the objects of my present invention is to provide a simpler and more economical form of combined socket cover and shade holder. Another object is to provide a form of socket cover which may be more quickly 10 wired and at the same time provide for its secure support. Another object is to provide for supporting glass shades in such a manner as to allow free expansion of the glass when heated by the lamp and to provide for ventilation. Reference is also made to my co-pending application Serial No. 128,537, filed 15 August 11, 1926, in which I utilize standard socket interiors with a minimum number of additional parts to form a complete fixture. 20 My present invention is also a specific development of this construction for the special uses which will be described.

In the accompanying drawings Fig. 1 is 25 the side view of an electric hanging fixture with the upper portion of the cable and the ceiling plate omitted; Fig. 2 is a horizontal view looking upward of the socket cover only; Fig. 3 is a vertical cross section of the parts shown in Fig. 1 with the lower portion 30 of the lamp and shade cut away and the cable and socket interior shown in side elevation; Fig. 4 is a top view of the socket interior only; Fig. 5 is a side view of the shade supporting ring; Fig. 6 is a horizontal view 35 looking upward of the shade supporting ring.

In carrying out my invention according to the illustrated embodiment thereof I provide a socket cover 1 of moulded insulating 40 material having an opening 2 for the passage of what is known in the trade as type SJ 2-conductor electric cable 4 and a chamber 3 adapted to accommodate a knot in the cable as shown. I also provide a standard 45 socket interior 5 having a base 6 of insulating material formed with two lugs 7, 7 extending beyond the diameter of the screw-shell of the socket and adapted to fit into two of the four notches 8, 8, 8, 8 formed in 50 the socket cover so as to provide a seat for the said lugs in the socket cover and to prevent rotation of the socket interior with respect to the socket cover. The lower end of the socket cover is provided with a number

of grooves 9 extending through from the inside to the outside thereof.

I also provide a shade supporting member 10 having a threaded portion 11 adapted to be passed through an opening in a shade and screw into the internal threads 12 of the 60 socket cover 1 and having a flange 13 larger than the opening of the shade to provide a support for the shade. A flange 13 provided with a member holes 14, 14 spaced on a diameter larger than the threaded portion 11 and smaller than the diameter of the opening in the shade. The shade supporting member 10 also has an internal cylindrical opening 15 large enough to slip the brass screw-shell of the socket interior 5 but too small to admit 70 the lugs 7. The length of the shade supporting member is such that when screwed into the socket cover the end 16 thereof is brought to bear against the lugs 7 to seat the socket interior firmly in position in the socket cover 75 and leave a vertical space between the diameter of the socket cover and the flange 13 slightly greater than the thickness of the glass shade 17.

It will thus be evident that the glass shade 80 rests upon the flange 13 and is secured against any material displacement therefrom by the end of the socket cover but that the shade is not gripped tightly between the socket cover and the flange 13 and may therefore expand 85 and contract freely in all changes of temperature.

It will also be observed that there is a ring 90 of space 18 between the edge of the glass shade and the neck of the shade supporting member. This space communicates with the grooves 9 above and the holes 14 below to provide a series of ventilating ducts through which the heated air on the inside of the shade may escape. As the space 18 is practically continuous even though the shade be shifted toward one side or the other of the holder, this ventilating means is effective 95 regardless of the angular position of the holes 14 with respect to the grooves 9. The simplicity of my improved construction will be further understood from the following description of how it is assembled:

The cable 4 is passed through the opening 2 in the socket cover 1 and out the opposite end. 100 A knot is tied near the end of the cable and the two conductors connected to the terminals 20 of the socket interior. The cable is then

- pulled back into the socket cover until the knot in the cable is seated in the chamber 3 and the socket interior put into place with the lugs 7 occupying two of the notches 8.
- 5 The shade supporting member 10 is then taken in one hand and inserted through the opening in the shade and screwed into the socket cover until it seats against the lugs 7. An electric lamp 19 may then be inserted 10 through the opening 15 and screwed into the socket.

It should be observed that my improved holder is especially adapted for shades which are open at the bottom or which have a bottom opening large enough to admit the operator's hand to screw the shade supporting member into place and also to admit the lamp. The shade is protected against falling while being assembled as it is resting on 15 the shade supporting member and over the operator's hand so that the other hand is quite free to hold the socket cover while the shade supporting member is screwed into it.

It will be understood, of course, that the 25 socket cover 1 may be adapted for rigid support on a wall or ceiling and a material part of my invention still remain and that various modifications in form and materials may be made. The invention herein described includes what I claim as new, which is:

1. An electric lighting fixture including a lamp socket member having a screw-shell, lugs carried by one portion of the socket member and projecting beyond the diameter of 35 the screw-shell, a socket cover having a threaded opening at its lower end large enough to pass the lug bearing portion of the socket member, spaced recesses in the socket cover above its threaded opening adapted to 40 accommodate the lugs to prevent rotation of the socket member with respect to the socket cover when the former is disposed within the latter, and a shade supporting member having an externally threaded central sleeve 45 adapted to screw into the threaded opening of the socket cover to surround the screw-shell and bear upwardly against the lugs of the socket member.

2. An electric lighting fixture including a 50 lamp socket member, a socket cover having a threaded opening, grooves in the end of the socket cover surrounding the threaded opening, a shade supporting member adapted to screw into the socket cover and having a

flange to support a shade and spaced openings in the flange adapted to co-operate with the grooves in the socket cover to provide ventilation for the shade.

3. An electric lighting fixture including a lamp socket member, a socket cover having a 55 threaded opening, radial grooves in the end of the socket cover surrounding the threaded opening, a shade supporting member adapted to screw into the socket cover and having a flange to support a shade, spaced openings in 60 the flange adapted to co-operate with the radial grooves in the socket cover to provide ventilation for the shade, and means integral with the lamp socket member to provide a stop for the shade holding member when 65 screwed into the socket cover to prevent tightening the shade holding member against the shade.

4. An electric lighting fixture comprising a lamp socket member having radial lugs projecting laterally therefrom and a depending screw-shell, a socket cover having an opening at its lower end for the insertion of said socket member and its screw shell therein and recesses above said opening to receive 75 said socket member lugs, and means separable 80 from said socket cover both to retain said socket member in place by engagement with said lugs thereof and to support a lamp shade in depending extension from the lower end 85 of said socket cover.

5. An electric lighting fixture comprising a lamp socket member having radial lugs projecting laterally therefrom and a depending screw-shell, a socket cover having an 90 internally threaded opening at its lower end for the insertion of said socket member and its screw shell therein and recesses above said opening to receive 95 said socket member lugs, and a combined socket member retaining means and lamp shade support, comprising an externally threaded sleeve to screw into said internally threaded opening of said socket cover around said screw-shell and to bear upwardly against said socket member lugs, and an outwardly extending annular shade-supporting flange at the lower exterior 100 end of said sleeve to underlie said socket cover.

Signed at New York, N. Y., on this 6th day 105 of October, 1926.

ERNEST CANTELO WHITE.
